UNITED STATES PATENT OFFICE

AUSTIN L. STOWELL, OF NEW BRITAIN, CONNECTICUT, ASSIGNOR TO THE STANLEY WORKS, OF NEW BRITAIN, CONNECTICUT, A CORPORATION OF CONNECTICUT

SCRAPER

Application filed October 6, 1931. Serial No. 567,207.

This invention relates to scraping tools, and has particular reference to a tool especially adapted for use in removing carbon from engine parts, such as the walls of cylinders, et cetera.

The aim of the invention is to provide an improved tool of this sort having various features of novelty and advantage, and which is particularly characterized by its effectiveness in operation and by its simplicity in construction.

The invention has in view a scraper provided with a scraping instrumentality comprising a plurality of wires each having a scraping edge at one end, the wires at their other ends being suitably anchored, and provision being made for adjusting the scraping instrumentality relative to a holder or body in order to vary the flexibility of the several wires. By preference, the wires are square or rectangular in cross section, and these wires are positioned side by side with their scraping edges normally transversely aligned but capable of being conveniently formed to curved or irregular surfaces.

Other objects will be in part obvious, and in part pointed out more in detail hereinafter.

The invention accordingly consists in the features of construction, combination of elements and arrangement of parts which will be exemplified in the construction herein-after set forth and the scope of the application of which will be indicated in the appended claims.

In the accompanying drawing, wherein is shown, for illustrative purposes, one of the embodiments which the present invention may take,

Fig. 1 is a top plan view of my improved tool;

Fig. 2 is a central longitudinal sectional view therethrough; and

Fig. 3 is a detail view of a clip with one of the scraping wires secured thereto.

Referring to the drawing in detail, A denotes generally a scraping instrumentality which is composed of a plurality of tempered steel spring wires 10 positioned side by side. Each of these wires, by preference,

is square or rectangular in cross section and has its forward end 11 bent downwardly and forwardly at an angle, as illustrated. The forward extremity of each wire is slightly beveled, as at 12, so as to form a cutting edge 13. Normally, the cutting edges 13 of the several wires are substantially aligned, although this is not necessary. Each wire has, adjacent its rear end, a curved hump 14.

The numeral 15 designates a clip, preferably formed of sheet metal and having a main plate portion with depending ears 16 at its opposite sides. The clip is transversely slotted, as at 17, and this slot extends down into the ear so as to form seats 18 for an anchoring pin 19. When the parts are assembled, as shown in Figs. 2 and 3, the humps 14 of the wires extend up into the slots 17 and the pin 19 holds these humps in place. The width of the scraping instrumentality is substantially equal to the distance between the ears 16 so that the several wires have no side play relative to the clip and, owing to the fact that the humps are held by the pin between the edges of the slots 17, the wires are held against longitudinal movement relative to the clip. The arrangement described provides a very simple, economical, and effective means for anchoring the wires to the clip.

The numeral 25 denotes a body or holder also preferably formed of sheet metal and comprising a relatively flat plate, the forward end of which is bent downwardly and forwardly so as to form a lip 26. This lip has a slot 27 through which the scraping instrumentality extends. The length of this slot is substantially equal to the width of the scraping instrumentality so that the wires will have no side play relative to the forward end of the holder. The body has a longitudinally extending slot 28. It also has a rearwardly extending shank 29 which is preferably curved or semi-circular in cross section. This shank is adapted to snugly fit in the bore 30 of a handle 31 and is secured in place therein by a transverse pin 32 or other suitable fastening means.

About the forward end of the handle is a metal ferrule 33. For the purpose of securing the scraping instrumentality in any desired position of adjustment relative to the holder or body, a screw 34 and a nut 35 are provided. This screw is adapted to extend through the longitudinally extending slot 28 in the holder and a hole 36 in the clip.

10 The manner in which the tool is used will be clear from the foregoing description, taken in connection with the accompanying drawing. When it is desired that the scraping instrumentality be relatively rigid, the clip is adjusted relative to the body 25, as shown in Figs. 1 and 2. When greater flexibility is desired, the nut 25 is loosened and the clip is moved forwardly of the holder (that is, to the left) so that 20 the wires will extend forwardly to a greater distance beyond the body, and then the nut is tightened up to lock the parts in adjusted position. When using the tool, the scraping edges are brought into engagement with the surface to be cleaned and then the tool is drawn towards the user; that is, to the right, referring to Figs. 1 and 2. Since the scraping instrumentality is made up of a plurality of wires adapted 30 to independently flex, the scraping edges 13 may readily accommodate themselves to surfaces of various shapes and to irregularities in the surfaces. Obviously, when pressure is placed upon the tool during 35 scraping operation, the wires will bear against the upper edge of the transverse slot 27 and more or less fulcrum or bend about that edge. It is of advantage to provide each of the several wires with a 40 straight scraping edge so that each wire will take a broad cut. When a flat surface is operated upon, such as the flat head of an aluminum piston, the wires will scrape that surface practically as smooth as a 45 single straight-edged blade would. Each of the wires has a greater amount of active cutting edge than is obtained with a round wire where practically all the work is done on a point, and the straight edge wire provides a tool which will stay sharp longer.

As many changes could be made in the above construction and many apparently widely different embodiments of this invention could be made without departing 55 from the scope thereof, it is intended that all matter contained in the above description or shown in the accompanying drawing shall be interpreted as illustrative and not in a limiting sense.

60 It is also to be understood that the language used in the following claims is intended to cover all of the generic and specific features of the invention herein described and all statements of the scope of 65 the invention which, as a matter of lan-

guage, might be said to fall therebetween. What is claimed is:

1. A scraping tool having a scraping instrumentality comprising a plurality of wires positioned side by side, the forward ends of said wires having scraping edges, a member to which said wires are connected, and a holder to which said member is adjustably connected, said holder having a portion against which said wires are adapted to engage. 70

2. A scraping tool having a plurality of wires positioned side by side and provided with scraping edges at their forward ends, a member to which said wires are anchored adjacent their rear ends, and a holder to which said member is adjustably connected, the scraping ends of said wires extending forwardly from said holder and said holder having an edge against which said wires are adapted to bear between their ends when 80 pressure is applied to the wires. 85

3. A scraping tool having a plurality of wires positioned side by side, the forward ends of said wires being bent at an angle and having scraping edges, a clip to which the rear ends of said wires are connected, a holder comprising a plate, and means for adjustably connecting said clip to said plate, said holder having at its forward end a bearing surface against which said wires are adapted to engage between their ends when 90 pressure is applied to the wires. 95

4. A scraping tool having a plurality of wires generally square in cross section and positioned side by side, the forward ends of said wires being bent downwardly at an angle and being provided with scraping edges at their extremities, a clip to which the rear ends of said wires are connected, a holder comprising a plate against which said clip is adapted to engage and provided with a longitudinally extending slot, and a screw extending through said slot and clip for adjustably connecting the parts together. 100

5. A scraping tool having a plurality of wires positioned side by side and provided with scraping edges at their forward extremities, a clip to which the rear ends of said wires are connected, a holder having a longitudinally extending slot, and means extending through said slot for adjustably connecting said clip to said holder, said holder at its forward end having a lip provided with a transverse slot through which said wires extend. 110

6. A scraping tool having a plurality of wires generally square in cross section and positioned side by side, by forward ends of said wires being bent downwardly at an angle and having scraping edges at their extremities, a clip to which the rear ends of said wires are connected, a holder comprising a plate-like member having a longitudinally extending slot and a down-turned 125 130

lip at its forward end provided with a transverse slot, said wires extending through said transverse slot, a screw extending through said first slot and said clip, and a nut on said

5 screw.

7. A scraping tool having a plurality of wires positioned side by side and provided with scraping edges at their forward extremities, said wires adjacent their rear ends 10 having curved humps, a clip having a slot and seats for a pin, and a pin engaging in said seats and fitting in said humps, said humps fitting in said slot.

8. A scraping tool having a scraping instrumentality comprising a plurality of wires positioned side by side, the forward ends of said wires having scraping edges, a member to which said wires are connected, and a second member embracing said wires 20 and having a portion against which said wires are adapted to engage, said wires and said second member being relatively adjustable.
